Specification for Design.

Patented Dec. 9, 1919.

Application filed November 25, 1918. Serial No. 264,113. Term of patent 14 years.

To all whom it may concern:

Be it known that I, WILLIAM A. E. MICHAELIS, a citizen of the United States, residing at Seattle, in the county of King and State of Washington, have invented a new, original, and ornamental Design for Vegetable-Knives, of which the following is a specification, reference being had to the accompanying drawing, forming part thereof.

What I claim, is—

The ornamental design for a vegetable knife, as shown.

WILLIAM A. E. MICHAELIS.
